TRANSMITTER UNIT FOR HYDRAULIC
TELEMOTOR SYSTEMS

Paul E. Forsythe, Seattle, Wash., assignor to
Webster-Brinkley Co., Seattle, Wash., a corpora-
tion of Washington

Application December 26, 1944, Serial No. 569,877

9 Claims. (Cl. 60—54.6)

1

This invention relates to the transmitter unit for a hydraulic telemotor system, and its principal object is to provide a perfected device of this nature employing twin and oppositely acting rams for the transmission of hydraulic pressure to the responding motor end of the telemotor system, and which said transmitter device, in more particularity, is essentially characterized in that the same operates automatically through activation of the transmitter's hand-wheel to constantly hold the oil bodies related to the two rams in a state of equalization and thereby maintain functional exactitude as between the associated transmitter and motor units of the system. To enlarge somewhat upon the above, the present invention, as with most hydraulic transmitter units as now customarily engineered, utilizes a replenishing tank from which hydraulic fluid is periodically supplied to the cylinders of the rams or, as may be necessary in the event of a temperature rise, into which oil may be bled from the cylinders, the purpose being to hold the oil bodies under a pressure condition substantially that of atmospheric and to at all times equalize the body of oil related to one in respect of the body of oil related to the other of the two rams.

As hydraulic telemotor systems were first designed, the necessary equalization to which reference is above had was achieved through the utilization of a hand-operated valve giving connection across the two ram-cylinders and with the replenishing tank and which a helmsman would operate when going on shift, or at such closer intervals as might be desired, performing this work with the hand-wheel placed in an amidships position. It was to be expected that an effort would be made to obviate this need for manual attention, and various automatic arrangements have accordingly been engineered. These automatic arrangements can be said to be of two types, one said type resorting to the use of wall ports which connect with the replenishing tank and which are cleared by the rams as the latter traverse their neutral positions, and the other said type employing mechanically operated closure valves actuated through various mechanical means responding directly or indirectly to the movements of the hand-wheel and similarly correlated to the rams such as to give access across the ram-cylinders and with the replenishing tank as the rams traverse neutral. The objection to the first-mentioned type lies in a tendency for leakage. Also, the ports must be extremely narrow in order that the oil bodies may be trapped and motor-operating impulses transmitted there-

2

by as the rams are caused to move out of neutral positions, the resulting constriction precluding a ready flow of replenishing oil. The other of the two types, and in which class the present invention falls, has been consequently favored by vessel operators, but the valve systems heretofore provided have not been completely satisfactory in that the same have a more or less common fault of failing to open the replenishing lines to full flow capacity at precisely the moment, and only at the moment, that the rams pass neutral. Otherwise stated, the open period has run somewhat beyond true neutral into the initial stage of a ram's working travel with the self-evident result that the steering wheel of the vessel, or which is to say the hand-wheel of the transmitter unit, fails to transmit operating impulses to the motor unit of the system until the wheel has moved through several degrees of travel.

The present invention aims to devise improved valve-opening mechanism producing an exceptionally fast action attaining a full opening and a following complete closing of the valves during a momentary interval in the travel of the rams to and beyond neutral which can be said to very nearly coincide with the exact neutral positioning of the rams.

The invention has the further and important object of providing a system including two independent sources of oil supply and, as an adjunct to automatically acting valves functionally associated with one said source, providing a separate and hand-operated valve associated with the other said source and enabling the transmitter unit to be kept in an operating condition in the event that it becomes necessary to repair or replace the automatically acting valves.

As a further object still, the invention aims to structurally improve the transmitter unit through incorporation of advanced reduction gearing—planetary in nature—between the hand-wheel and the rams toward minimizing the energy necessarily exerted in giving motor-operating movements to the latter.

A still further object of the invention is to provide a transmitter unit of the described character so engineered as to adapt this reduction drive to the movements of either of two selectively employed wheels, one a primary wheel carried directly by and made a part of the transmitter unit proper and the other a secondary and remote wheel, for example the wheel found upon the flying bridge of a vessel.

With the foregoing and still further objects and advantages in view, and which will appear and be

understood in the course of the following description and claims, the invention consists in the novel construction and in the adaptation and combination of parts hereinafter described and claimed.

In the accompanying drawings—

Figure 1 is a vertical sectional view taken on the substantial longitudinal median line of a transmitter unit having its parts constructed and arranged according to the now preferred embodiment of the invention, the view being fragmentary in part to the extent, principally, that only the tail end of the remote-control connection leading, say, from a flying bridge is shown in the view, parts of the oil-conducting pipes are deleted, and a partitioning wall which lies between two compartments—the hereinbefore mentioned separate sources of oil supply—of the replenishing tank is broken away to give a clear portrayal of the particular chamber from which the several illustrated oil-supply pipes draw their replenishing fluid.

Fig. 2 is a transverse vertical section on line 2—2 of Fig. 1.

Fig. 3 is a fragmentary transverse vertical section taken to an enlarged scale on line 3—3 of Fig. 1.

Fig. 4 is a fragmentary transverse vertical section on line 4—4 of Fig. 1.

Fig. 5 is a horizontal section taken to an enlarged scale on line 5—5 of Fig. 1; and

Fig. 6 is a fragmentary transverse vertical section taken to an enlarged scale on line 6—6 of Fig. 5.

Referring to said drawings, the numeral 1 denotes a wheel-stand arranged and adapted to be fixedly secured upon the bridge-deck of a marine vessel and formed to provide, at its lower end, companion parallel cylinders 8 and 9 of a diameter somewhat greater than that of the pistons or rams 10 and 11 which work therein. The usual stuffing-box assemblies are applied to the upper open ends of the cylinders.

Occupying perpendicular positions, said rams extend by their upper ends into a gear chamber produced in the head part of the stand, and are coupled to spaced-apart racks 12 and 13 aligned therewith and which are guidably supported for reciprocatory vertical movement. A driving pinion 14 for the racks, and which is disposed to mesh the latter from a position therebetween, is made integral with a hub element extended as an axial prolongation from a planet spider 15, and this spider, with its complement in a second and axially aligned planet spider 16, produces a cage by which to revolvably support a severality of planet gears 17. 18 designates the journal pins for these gears.

The said spiders, and which extend through and receive a rotary mounting in opposite end walls of the wheel-stand, are each center-bored, and there is received through these registering center-bores a main shaft 22 with suitable bushings being provided to admit of free relative rotation as between the planetary cage and the shaft. The shaft extends by each of its two ends outwardly beyond the end limits of the cage, or which is to say beyond the spider hubs, and there is formed upon the shaft to occupy a position between the spiders a sun gear 23 in mesh with the teeth of the planet gears. Completing the planetary gearing is an internal gear 24 held stationary by the wheel-stand.

The hand-wheel for the transmitter unit is indicated by 25, and is fitted with a bushing 26

which finds a rotary journal upon the exposed front end of the main shaft, and for purposes of releasably coupling the wheel to the shaft there is splined upon the shaft a jaw-clutch 27 manually shiftable in an axial direction and by such shifting bringing the clutching teeth into couple with mating teeth produced upon the frontal face of the wheel.

Denoted by 28, there is fixedly applied to the exposed rear end of the main shaft a miter gear arranged and adapted to mesh a second miter gear 29, and powering this latter gear is a normally inactive stub shaft 30 carried for rotary movement about a perpendicular axis. The first-named miter gear, and for a purpose which will hereinafter appear, is formed with a somewhat extended hub and introduced between this hub and the projecting end of the hub prolongation of spider 15 is a suitable thrust bearing. The said stub shaft has a jaw-clutch element 31 fixedly applied to its upper end, and as a complement thereto there is provided a second jaw-clutch element 32 splined to and axially shiftable upon a driving shaft 33 which is powered, through a universal connection, from an auxiliary steering wheel (not shown). The stub shaft and its complementing drive shaft are given a coaxial mounting in a bracket 34 boltably attached to the back wall of the wheel-stand, and suspended from this bracket to guard the otherwise exposed miter gears is a plate 35. Detailed in respect of the last-described jaw-clutch assembly, and represented by dotted lines in respect of the first-described jaw-clutch assembly, is a bullet catch comprised of the customary spring-pressed ball 36 arranged to find engagement in either of two axially-spaced surface recesses.

It will be apparent from the foregoing that the main shaft may derive its power from the hand movements given to either of two selectively employed steering wheels. As the main shaft turns in concert with this selected wheel, the planet gears walk about the internal gear 24 and give to the cage a reduced-speed rotary travel in the same direction as the shaft, transmitting through pinion 14 to the twin racks the oppositely directed rectilinear travel which will cause one ram to express oil from its cylinder through a related oil pipe 37 while the other ram draws oil into its cylinder through pipe 38, these two pipes making connection by their other ends with the motor end of the telemotor system. The wheel-stand is provided with the usual indicator dial, and to operate the pointer therefor, indicated at 39, employs bevel gears 40 driven from a rock-shaft 41 to which is pinned a gear segment 41 in mesh with the pinion 14.

Now describing the means by which equalization is automatically obtained as between the oil bodies in the two motor-control lines as the rams traverse neutral in response to hand movements given to the wheel, the supply tank which is parent to these two lines is denoted by 42 and occupies a position to the rear of the stand proper subjacent to the exposed tail ends of said main shaft and the spider 15 and such as will place the level of the liquid therein above the upper limit of the ram cylinders. This tank is divided by a partitioning wall 43 into two ostensibly isolated compartments—a main compartment 44 and a reserve compartment 45—and is filled through a top opening normally closed by a vented filling plug 46. Drain plugs (not shown) are provided for said compartments, and there is also provided a liquid-level gauge, as 47. Access

to the main compartment is obtained through the provision of a hand-hole normally sealed by a cover 48.

Said main compartment, in its bottom wall, presents two through-openings which are so located as to occupy positions spaced equidistantly at opposite sides, transversely considered, of a perpendicular dropped from the axial line of the main shaft 22. Related to and closing these holes are tubular neck elements extending upwardly into the liquid contents of the tank and giving access to the tank from valve chambers provided in valve bodies, as 49 and 50, these valve chambers being perpendicularly aligned with the neck ducts and having a diameter somewhat enlarged from the latter to produce seats for ball checks 51 at the point of juncture between said chambers and the ducts. Springs 52 act upon the ball checks to urge the latter into seated positions. Oil-conducting pipes, as 53 and 54, connect by side-arm branches with the respective valve chambers and make connection by their opposite ends one with the oil cylinder 8 and the other with the oil cylinder 9, the latter connection being desirably made to one branch of a respective T-fitting 55. There is provided for each of said oil pipes a normally open shut-off cock (not shown), and a desirable arrangement is one in which this cock is carried by and becomes a part of the branch arm of the T-fitting to which the pipe is attached.

Reverting to the ball checks, the same are caused to be unseated against the resistance offered by the springs through the action of valve rods 56-57 which work freely through the neck ducts and are adjustably carried as perpendicular dependencies of a yoking cross-arm 58, and fixedly carrying this yoke is a push-rod 60 guided by and extending for vertical sliding movement through the head wall of the tank. Functional upon the push-rod to urge the latter upwardly is a spring 59. This push-rod has a rocker-arm 62 carried upon its exposed head extremity, and below said arm presents a chordal slot 61, and associated with this slot is a stationary stop bar 63 which serves the two-fold end of resisting rotation of the push-rod and of limiting the spring urged upward travel of the latter.

The rocker-arm is of a bowed form presenting upwardly turned furcate extremities, and within its length there is provided an offset which serves to place one of these forked ends in a transverse vertical plane common to the exposed rear extremity of the spider 15 and the other forked end in a transverse vertical plane common to the aforementioned hub of the miter gear 28. Rollers, as 64 and 65, are carried by these forked ends for rotary movement about axes paralleling that of the main shaft, and functional upon such rollers are respective cams 66 and 67 one of which is fixedly sleeved upon the tail end of the spider and the other upon the said hub of the miter gear. Such cams performe turn at different speeds and, to reflect the reduction ratio—approximately 1 to 7½—which obtains between the spider and the main shaft, and hence between the respective cams 66 and 27, these two cams will be herein-after termed the slow and the fast cam, respectively. As will be apparent from an inspection of Fig. 3, the development of the roller-activating eccentric faces of these cams is different, the rise of the slow cam being comparatively minor and progressing to an arched median crest while the fast cam develops quite rapidly to a sharp median crest. The two cams are enabled to depress the

push-rod only when the same act upon the two rollers in concert and, in this concerted action, the compounding of the two thrusts is such as will produce an extremely fast valve-opening action. The arrangement has the further advantage of softening the camming thrust and largely cancelling out the lateral bind customarily associated with a single fast-acting cam. Considering, moreover, that the two cams work at different precise speeds, it becomes possible to swing the rudder hardover through the impartation of several turns to the steering wheel without, in so doing, effecting the push-rod as the fast cam passes center, and which is to say that the two cams will occupy the positions necessary to act in unison upon the respective rollers only at substantially the exact moment when the two wheel-responsive rams lie in coinciding or neutral positions. It may be pointed out that the rocker arm is suitably weighted on the fast-cam end in order that the roller 65 will be positioned out of the path of travel of the fast-cam excepting when the opposite end is held in a depressed position, relatively speaking, in consequence of the slow cam occupying the position in which it is illustrated in Fig. 3. The weighting may be readily accomplished by boring the fast-cam end of the rocker-arm and filling with molten lead.

In addition to the above-described means by which movements of the hand-wheel of the transmitter unit are made operative, automatically, to periodically equalize the two hydraulic transmitter lines, it becomes desirable to introduce means by which the equalization can be accomplished through a hand control and which, under certain circumstances, can be set to develop and maintain a condition which will give constant connection across the two ram-cylinders. The purpose as respects said manually-controlled equalizing is to enable the main compartment of the replenishing tank to be completely isolated for draining and, when so drained, permitting the ball checks or any part of the mechanism related thereto to be replaced or repaired should the need therefor arise without, during such period, cutting out the transmitter unit. The maintaining of a constant connection across the two ram-cylinders becomes desirable under circumstances where recourse, for steering, is had to a vessel's stern helm and, to enable the motor end of the telemotor system to operate freely without the resistant load of the rams and associated parts of the transmitter unit, it becomes necessary to isolate the working parts of the transmitter unit and give free passage to the oil from one to another of the two oil columns.

In permitting either of said ends to be attained, I bypass the main compartment of the replenishing tank by providing a connection, as 70, leading from the reserve compartment 45 to a valve body 71, and connecting this valve body by branch lines 72-73 to the two ram-cylinders, the said lines 72 and 73 making connection with the cylinders by means of the other branches of the referred-to T-fittings 55. The valve body here referred to is formed with co-axially disposed valve chambers 74 and 75 separated by a connecting passage 76, and has respective ports—as 77, 78 and 79—for each said chamber and for the passage connecting, as respects the valve chambers, with the oil pipes 72 and 73 and, as respects the passage, with the oil pipe 70. Ball valves 80 and 81 received in the valve chambers and made subject to the force of spring 82 normally isolate the center 76 passage from the chambers, and functional upon

these valves for unseating the same are push-rods 83 and 84. The push-rods abut the camming end of a spindle 85, and fixed to the exposed head of this spindle is an operating handle 86 which is given a limited range of movement through employment of a pin 87 tracking in a slot 88. A bullet catch is provided to releasably hold the handle in operative or inoperative positions, selectively. In using the by-pass line it will be understood that the cocks for the two oil-conducting pipes 53 and 54 are closed, and the helmsman, upon placing the hand-wheel in a neutral position, opens and again closes the two ball valves 80 and 81 by activation of the handle 86. If the transmitter unit is to be made inactive, the handle is turned to its valve-opening position and left in such position.

It is believed unnecessary to here trace the operation of the system other than, perhaps, to expressly consider the working of the fluid-equalizing valves 51 and the operating instrumentality therefor. The parts, as they are illustrated in Fig. 3, lie in the positions which they occupy when the steering wheel and the responding rams 10-11 are in neutral. Both rollers 64 and 65 are depressed, each in consequence of its related cam having been brought into a position whereat its highest point is in contact with the roller, and this simultaneous depression forces the rocker-arm 62 bodily downwardly with a resulting depression of the push-rod 60. The push-rod acts through the crossarm 58 to depress the two valve rods 56 and 57 which, in turn, open the two valves 51, and such opening of the valves produces a communication from one to the other valve chamber of the two valve bodies 49 and 50 as connection is had from each said valve chamber with the reservoir. Assume, now, that the helmsman in the performance of his steering office swings the steering wheel out of neutral, the sharp crest of the fast cam 67-tied directly to the wheel by means of the shaft 22-instantly falls away from the roller, and the latter, by force of the spring 59, rises about the center of the as-yet depressed roller 64 as an axis and the fulcrum of the rocker-arm 62 perforce rises with the rise of the said roller 65. Such elevation of the fulcrum-point of the rocker-arm lifts the push-rod, the cross-arm, and the valve rods, allowing the valves 51 to close by force of the springs 52, and this valve-closing action is completed by practically negligible movement of the steering wheel out of neutral. Roller 64 will, of course, continue to maintain contact with the slow cam 66, although perforce progressively falling away from the high point. As the same has been illustrated, the slow cam has a total span of approximately 60°, and by this token the roller 64 will be free of the cam when the slow cam has been turned a total of 30° from the neutral position shown in Fig. 3. Considering that the ratio between the fast and the slow cam is approximately 7½ to 1, it follows that the slow cam will move approximately 48° as the fast cam moves 360°, and hence the slow cam will have left the roller 64 and moved through an additional arc of 18° before the fast cam has completed one revolution of turn from neutral. Due to the weighting of the fast-cam end of the rocker-arm, this end will drop as the other end is permitted to rise in consequence of the cam 66 being withdrawn from roller 64, and what might otherwise be an objectionable "slapping" of the roller 65 as the fast cam 67 completes the first and successive following revolutions of a number of wheel

turns is precluded. Seven and one-half turns of the steering wheel would perforce be necessary to give 360° of travel to the slow cam, or which is to say again bring the peak of the slow cam against the roller 64, and, at this particular point in the travel of the slow cam, the fast cam 67 will occupy a position diametrically opposite the position of Fig. 3 and hence be inactive to the roller 65. When turned the additional half-turn 10 which would be necessary to contact the roller 65, the slow cam will have travelled an added 24° and the contact between cam 66 and roller 64 will be on the low point of the cam 66 to elevate said roller 64 and responsively lower the 15 roller 65 in a degree sufficient to clear the fast cam as the latter passes thereover. From the foregoing, it will be readily apparent that, using the stated 7½ to 1 ratio, a total of fifteen complete turns of the steering wheel would be required in order that the two cams simultaneously arrive at points coinciding with the positions which they occupy when the wheel is at neutral. This number of turns is well above any "hard over" usage of the wheel, and which is to say 20 that a steering wheel is never turned to this extent. Numerous departures from the illustrated and described embodiment will suggest themselves having knowledge of my teachings, and it is self-evident that recourse may be freely 25 had thereto without sacrifice of the inventive concept. It is my intention that all forms of construction and variation in detail coming within the scope of the hereto annexed claims are 30 to be considered as comprehended by the invention.

What I claim, is:

1. A hydraulic control apparatus comprising, in combination with a control wheel swingable in opposite directions from a neutral position, and with a hydraulic impulse-transmitting system providing a pair of operating cylinders and rams for said cylinders, the rams being operatively interconnected with the wheel to cause the rams to move oppositely from neutral positions 40 by movements of the wheel from neutral: an oil-replenishing tank having separate and parallel delivery ducts extending through the bottom wall thereof and making connection one with one and the other with the other of the two ram-cylinders; spring-urged valves for said ducts closing against the weight of the oil within the tank; a push-rod extending into the oil within the tank and fitted upon its lower end with thrust stems registering with said delivery ducts and 45 functional by depression of the rod to engage and unseat the valves; a rocker arm supported upon the head end of the push-rod; a pair of rotary cams, mechanisms providing operative interconnection from the control wheel to the two cams and serving to power the cams relatively in unison one with another and with the control wheel 50 but with one cam operating at a different rotary speed than the other cam, said cams acting one to engage one end and the other to engage the other end of the rocker arm, and having their eccentricities so placed and developed as to depress the push-rod by concerted action of the two cams only as the control wheel occupies its neutral position.
2. In a hydraulic control apparatus having a control wheel swingable in opposite directions from a neutral position, and providing a hydraulic impulse-transmitting system employing a pair of operating cylinders and rams for said cylinders, 55 the rams being operatively interconnected with

the wheel to cause the rams to move oppositely from neutral positions by movements of the wheel from neutral, automatic means for equalizing the oil within the said impulse-transmitting system and comprising: an oil-replenishing tank having connection by separate fluid-flow lines with the two ram-cylinders; spring-urged valves for said fluid-flow lines closing against the weight of the oil within the tank; a push-rod functional to said valves and acting to open the same by movement in one direction of its endwise travel; a spring opposing said valve-opening movement of the push-rod; a rocker arm carried by the push-rod for rocker movements about an axis transverse to the latter's slide axis; a pair of rotary cams; means connecting the control wheel with one of the cams and imparting rotary motion thereto; and means also connecting the control wheel with the other cam to likewise impart rotary motion to the last-mentioned cam but characterized in that the rotation transmitted is of a different speed than the rotation transmitted to the first-mentioned cam; said cams acting one to engage one end and the other to engage the other end of the rocker arm, and having their eccentricities so placed and developed as to impart valve-opening movement to the push-rod, by action of the two cams working in concert, only as the control wheel occupies its said neutral position.

3. In a hydraulic control apparatus having a control wheel swingable in opposite directions from a neutral position, and providing a hydraulic impulse-transmitting system employing a pair of operating cylinders and rams for said cylinders, the rams being operatively interconnected with the wheel to cause the rams to move oppositely from neutral position by movements of the wheel from neutral, automatic means for equalizing the oil within the said impulse-transmitting system and comprising: an oil-replenishing tank having gravity-flow connection by separate fluid-flow lines with the two ram-cylinders; valves for said fluid-flow lines closing against the weight of the oil within the tank; springs influencing said valves into closed positions; a rocker arm supported for rocker movements about a transverse median axis and also admitting to bodily reciprocal movement in a median path at right angles to said rocker axis; operative interconnection from the rocker arm to the valves causing the latter to open against the resistance of the springs by bodily movement of said rocker arm in one direction of its said reciprocal travel; a pair of rotary cams; means connecting the control wheel with one of the cams and imparting rotary motion thereto; and means also connecting the control wheel with the other cam to likewise impart rotary motion to the last-mentioned cam but characterized in that the rotation transmitted is of a different speed than the rotation to the first-mentioned cam, said cams being operatively interconnected with the control wheel such that the cams are driven by the latter at different rotary speeds, one cam in relation to the other cam, said cams being functionally associated one with one and the other with the other end of the rocker arm, and having their eccentricities so placed and developed as to impart valve-opening bodily movement to the rocker arm, by action of the two cams working in concert, only as the control wheel occupies its said neutral position.

4. Structure according to claim 3 in which the two cams are co-axially mounted.

5. Structure according to claim 3 in which the two cams are mounted for rotation about a common axis coinciding with that of the control wheel, one of said cams being direct-driven from the wheel to turn with the latter at the same speed and in the same rotary direction, and wherein the powering connection from the wheel to the other said cam comprises planetary reduction gearing.

6. The structure of claim 3 in which the eccentricity of the slower-moving of the two cams is such as gives a gradual development, and in which that of the other and faster-moving cam is quite abrupt.

7. A hydraulic control apparatus comprising, in combination with a control wheel swingable in opposite rotary directions to and from a neutral position, and with a hydraulic impulse-transmitting system employing a pair of operating cylinders and oppositely acting rams for said cylinders: a main shaft rotatively responding to swinging movements of the wheel and having a sun gear and a cam element carried in axially spaced relation thereon; a stationary gear wheel placed proximate to the sun gear and concentric with the shaft; a hollow shaft received over said main shaft for relative rotation about a coincident axis, and occupying a position between the sun gear and the cam to extend by its ends into proximity of the latter, said hollow shaft being formed intermediate its length with external pinion teeth, having a spider element upon the end thereof which lies proximate to the sun gear, and carrying a cam element upon the other end; planet gears carried by said spider and functionally associated with the sun gear and the stationary gear wheel to cause the hollow shaft, by rotation given to the main shaft, to turn in concert with the main shaft but at a reduced rotary speed; racks engaging said pinion teeth and connected to and operating the rams such as will cause the rams to work in opposition, functionally considered, and directly toward and from neutral positions coincident with swing movements of the control wheel into and from neutral; an oil-replenishing tank having gravity-flow connection by separate fluid-flow lines with the two ram-cylinders; closure valves for the fluid-flow lines; springs functional upon the valves to influence the latter into their closed positions; a walking beam supported to lie transverse to the axis of said shafts subjacent to the cams and, in addition to its permitted rocker movement, admitting to bodily movement along a slide axis radial to said axis of the shafts; rollers functionally associated one with one and the other with the other of the two cams and rotatively journaled in the free ends of the walking beam to occupy positions restricted to the rotary path of travel of a respective said cam; and operative interconnection from said walking beam to the two valves causing the valves to open against the resistance of the springs by bodily depressing the walking beam, said cams having their eccentricities so placed and developed as to impart said valve-opening bodily movement to the walking beam, by action of the two cams working in concert, only as the control wheel occupies its said neutral position.

8. Hydraulic control apparatus according to claim 7 characterized in that the end of the walking beam related to the faster-moving of the two cams is weighted in respect of the beam's other end.

9. In a hydraulic control apparatus having a control wheel swingable in opposite directions from a neutral position, and providing a hydraulic impulse-transmitting system employing a pair of operating cylinders and rams for said cylinders, the rams being operatively interconnected with the wheel to cause the rams to move oppositely from neutral positions by movements of the wheel from neutral, automatic means for equalizing the oil within the said impulse-transmitting system and comprising, in combination: an oil-replenishing tank having connection by separate fluid-flow lines with the two ram-cylinders; spring-closing valves for the respective lines; means for opening said valves against the pressure of the springs; a pair of rotary cams; means connecting the control wheel with one of the cams for imparting rotary motion thereto; means also connecting the control wheel with the other cam to likewise impart rotary motion to the last-mentioned cam but characterized in that the rotation transmitted is of a different speed than the rotation transmitted to the cam

5
